UNITED STATES PATENT OFFICE.

SYLVANUS A. DENIO, OF BOSTON, MASSACHUSETTS.

IMPROVEMENT IN LOCKS FOR PRISON-DOORS.

Specification forming part of Letters Patent No. 173,775, dated February 22, 1876; application filed January 21, 1876.

To all whom it may concern:

Be it known that I, SYLVANUS A. DENIO, of Boston, in the county of Suffolk and State of Massachusetts, have invented certain Improvements in Locks for Prison-Doors, of which the following is a full, clear, and exact description, reference being had to the accompanying drawings, making part of this specification, in which—

Figure 1 is a perspective view of a prison-door lock constructed in accordance with my invention. Fig. 2 is a horizontal section through the same. Fig. 3 is a vertical section on the line xx of Fig. 2. Fig. 4 is an elevation of the check-lock with its front plate removed. Fig. 5 is an elevation of the check-lock, the front plate and tumblers being removed.

In the ordinary prison-door lock, the cam-shaft by which the main bolt is operated is locked, after the bolt has been thrown out, by the bolt of an ordinary spring-lock, termed the "check-lock," the latter bolt being thrown forward by its spring into the path of rotation of a projection on the cam-shaft, which is thus prevented from being moved to withdraw the main bolt. With this construction, when the cell is unlocked as is generally the case when it is not in use, the bolt of the check-lock is held back against the resistance of its spring, which is liable to become set, so that it will not throw out the check-bolt, and the lock is thus rendered worthless.

To overcome this difficulty is the object of my invention, which consists in the combination, with the cam-shaft of the main bolt, of a drop bolt or latch, which falls by its own weight into a position to prevent the rotation of the cam-shaft after the main bolt has been thrown out, the drop bolt being raised to release the cam-shaft by a suitable key, by which construction the spring heretofore used is dispensed with, and the lock rendered at all times reliable.

To enable others skilled in the art to understand and use my invention, I will proceed to describe the manner in which I have carried it out.

In the said drawings, A represents the casing

of the lock, and B the main bolt, which is operated by a cam, a , near one end of a horizontal shaft, b , having its bearings in the casing, and carrying at its opposite end a handle, c . The cam-shaft b is provided, near the end to which the handle is secured, with a projection, d , the upper surface of which is concentric with the shaft, and on this projection rests the outer end of a drop bolt or latch, C, which is pivoted at e within the casing D of the check-lock, its outer portion being made heavy to insure its dropping by its own weight as soon as the cam-shaft has been rotated sufficiently to carry the projection d out of contact with the end of the latch, which takes place as soon as the main bolt B has been thrown out. When the parts are in this position, as seen in Fig. 3, the cam-shaft is securely locked, and the bolt B cannot be withdrawn until the latch C of the check-lock is raised by the key f , which acts on its under side, as seen in Fig. 5.

It will thus be seen that, as the drop-latch falls by its own weight, it is always ready to act, and consequently there is no liability of the lock getting out of order, as is the case where an ordinary spring check-lock is employed.

To the inside of the casing D, near its top, is pivoted the upper end of a lever, g , which extends down into a position to be moved by the key f against the resistance of a spring, h . On one side of this lever g is a curved projection, i , which, when the latch drops, is thrown by the spring h into a space made to receive it between the latch and a projection, k , on the casing, the projection i thus serving as a bolt or stop to effectually lock or secure the latch, which cannot be raised until the projection is withdrawn by the key, thus affording additional security. From the front face of the lever g projects a stump, l , which passes through the slots of the tumblers m , which must first be raised by the key into their proper relative positions to allow the lever to be moved so as to withdraw the projection i . These tumblers, however, form no part of my invention, and may be dispensed with, if desired, although I prefer to employ them on account of the security which they afford. $n p$

are two stop-pins, which intercept the projection *d* and limit the rotation of the cam-shaft in either direction.

What I claim as my invention, and desire to secure by Letters Patent, is—

1. The drop bolt or latch *C*, in combination with the cam-shaft *b* and main bolt *B*, operating substantially in the manner and for the purpose set forth.

2. I also claim, in combination with the

weighted drop-latch *C*, cam-shaft *b*, and main bolt *B*, the bolt or stop *i*, for locking the latch when down, substantially as described.

Witness my hand this 17th day of January, A. D. 1876.

SYLVANUS A. DENIO.

In presence of—

P. E. TESCHEMACHER,
W. J. CAMBRIDGE.
